Primary Examiner — Rhea Shields

(74) Attorney, Agent, or Firm — Guy McClung

(57) **CLAIM**

The ornamental design for a box structure, as shown.

DESCRIPTION

FIG. 1 is a perspective view of a box structure showing my new design.

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.
